UNITED STATES PATENT OFFICE.

FREDERICK L. FULLER, OF DAYTON, OHIO, ASSIGNOR TO THE NATIONAL CASH REGISTER COMPANY, OF DAYTON, OHIO, A CORPORATION OF OHIO, (INCORPORATED IN 1906.)

ADDING MECHANISM.

1,088,068.

Specification of Letters Patent. Patented Feb. 24, 1914.

Application filed August 13, 1909. Serial No. 512,696.

To all whom it may concern:

Be it known that I, FREDERICK L. FULLER, a citizen of the United States, residing at Dayton, in the county of Montgomery and State of Ohio, have invented certain new and useful Improvements in Adding Mechanisms, of which the following is a specification.

My invention relates to adding mechanisms, such as are used in calculating machines, cash registers, and analogous constructions, and has for its object the production of a simple and positively operated mechanism, adapted to the addition of selected numerals.

In the accompanying drawings, forming a part of this specification, I have illustrated my adding mechanism or counter in connection with sufficient means to operate the same. Such illustrations as I have given show that part of an ordinary adding machine embodying my construction, which is sufficient to fully illustrate my invention, but without the inclusion of other parts of such a machine which are commonly used to indicate and register or record the results of the operation of the mechanism.

In the drawings Figure 1 shows a top view of a calculating machine embodying my invention, a part of the case being broken away to disclose portions of the mechanism within: Fig. 2 shows a side view of a portion of a calculating machine containing my invention, with a part of the side of the case broken away: Fig. 3 is a detail view showing one form of a driving mechanism for operating the adding device, being an end view of said operating device and the connections: Fig. 4 represents a longitudinal view of the main or actuating shaft of the driving mechanism with a central longitudinal sectional view of the driving sectors and their hubs, and the cam wheel used to throw the adding mechanism into position for action: Fig. 5 is a detail plan view of a portion of the adding mechanism: Fig. 6 is a sectional view of the mechanism shown in Fig. 5: Fig. 7 is an end view of the adding mechanism or counter with one of its end frames removed: Fig. 8 is a similar view to that shown in Fig. 7, but illustrating the parts in different relative

positions: Fig. 9 is a plan view of a complete section of the adding mechanism: Fig. 10 is a plan view of an actuating detent and its secondary cam, and another of said detents and secondary cams shown in section: Fig. 11 is an end view of the adding mechanism with one end frame removed showing the parts of the mechanism in a position different from that shown in the preceding figures: Fig. 12 is a view of the parts shown in Fig. 11, but in a yet different position; and Fig. 13 is a front view of mechanism used in the final operation of addition, and in releasing the adding mechanism for renewed action of its parts.

My construction is so arranged that the desired numbers can be selected, indicated and added or totalized, and the means for accomplishing this I shall now describe.

In Fig. 1 I have disclosed my adding mechanism proper in connection with one form of mechanism for operating the same, but it will be understood that the adding mechanism itself can be combined with a variety of means for producing this result. In the particular construction which I have illustrated in the drawings the apparatus is inclosed in a case 1, the top or cover of which contains nine slots 2, 2, four of which are shown in Fig. 1. Beside each of these slots, or between each two thereof, are arranged the numerals from naught to nine inclusive, as shown, to guide the operator in the manipulation of the machine. Operated through each of said slots is a knob or handle 3, with a pointer 4, to guide the eye to the desired numeral on the case. Each of these knobs, 3, is attached to a rack, 5, which slides within the case of the machine, and is shown in Figs. 2 and 3, each of which racks, 5, meshes with a segment 6, mounted loosely on the actuating shaft 7. Rigidly attached to the shaft 7 are the arms 8, to the lower ends of which is fixed the rock shaft 9. At one end of said shaft 7 is pinned the operating lever 10, which is shown in its normal position in Fig. 2. Loosely mounted upon the shaft 7 is the cam wheel 11, which has five cam surfaces equally spaced on its periphery, also fast to the shaft 7 is the arm 12, upon which is mounted the spring pressed plunger 13, which bears constantly

against the edge of the cam wheel 11, and partially rotates the same when the operating handle 10 is moved. On the shaft 14, journaled at its ends in the sides of said case of the machine, are mounted the end-frames 15, which contain the adding device proper. Mounted on the right hand end-frame, 15, is the roller 16, which contacts with the cam wheel 11. Mounted on and rigidly attached to each end-frame, 15, is the shaft, 17, on which are loosely mounted a series of indicating disks, 18, bearing the numerals on their peripheries, to each of which indicating disks is rigidly attached a gear wheel 19; and it will be noted that said several disks are spaced from each other and retain their relative positions by means of the hubs 20. Rigidly mounted in said end-frame, 15, is the shaft, 21, parallel to the shaft, 17, and below the same. On said shaft 21 are loosely mounted a series of actuating detents, 22, of anchor or pallet formation corresponding in number with the indicating disks. Also loosely mounted on said shaft 21 is a series of secondary cams, 23, corresponding in number with said actuating detents, 22, and alternating therewith.

Rigidly mounted in the end-frames, 15, is the shaft 24, on which are loosely mounted a series of detents 25, corresponding in number with said secondary cams 23, and respectively held in contact therewith by the series of helical springs 26 which serve to hold said detents 25 and actuating detents 22 in their normal positions, and return them thereto after action. Rigidly attached to the shaft 14 are a series of spirally arranged primary cams, 27, one less in number than the indicating disks, 18, and respectively positioned in the paths of the corresponding secondary cams 23. On the left hand face of each of the indicating disks, 18, and opposite the numeral 4 on the periphery thereof, except on the extreme left hand indicating disk, is fixed a stud, 28, which in its path contacts with the secondary cam, 23, next to the left of the disk, 18, on which said stud is placed. On the left hand face of each of said secondary cams, 23, is fixed a stud, 29, which projects perpendicularly from the face of its cam, 23, and under the actuating detent, 22, with which it may contact. (See Figs. 7, 8, 11 and 12). Rigidly mounted on the shaft, 7, near the left end thereof, is a geared sector, 30, and rigidly attached to the adjacent side of the case of the machine is the stud 31. On this stud 31 are revolvably mounted the pinion, 32, and the eccentric 33; and to the said eccentric is strapped the rack, 34, which meshes with the pinion, 35, rigidly fixed on the shaft 14. Fixed to the pinion, 32, is the disk, 36; while fixed to the eccentric, 33, is the sleeve, 37, having a transverse notch in

its periphery. Swinging on a stud on the face of the disk, 36, is the pawl, 38, the nose or point whereof is arranged to catch in said notch on the periphery of the sleeve, 37, when the pawl is driven forward, and to withdraw therefrom when forced backward, and the nose of said pawl is held in constant contact with said sleeve, 37, by the spring, 39, sustained by another stud fixed in the face of said disk, 36. (See Figs. 1, 2 and 13.)

My invention is operated as follows: Assuming the several parts of the machine to be in the primary or normal positions, shown in Figs. 1 and 2, the zeros on the peripheries of the several indicating disks, 18, are visible through the openings 40 in the case, and the several knobs, 3, and their pointers, 4, are below the zeros marked externally upon the case. To select and add any numerals, the desired numerals in units, tens, or hundreds are determined by moving the proper knobs, 3, until their pointers respectively stand opposite the several selected numerals as indicated on the case. As each of said knobs, 3, is moved forward to its position opposite the selected numeral, the rack, 5, to which said knob is attached is moved the same distance, and the teeth on such rack meshing with the teeth on the particular sector, 6, to be actuated by said rack, turn back the said sector as many fiftieths of an entire revolution thereof as there are units in the numeral selected. The several knobs, 3, having been brought opposite the selected numerals indicated on the case, the lever 10 is thrown forward from its normal position indicated in Fig. 2 one-fifth of a complete revolution, when it is stopped by the lug, 41, on the outside of the case. By this motion of the said lever the cam-wheel 11 is turned one fifth of a revolution, and the roller 16 is forced up upon the periphery of said cam-wheel, whereby the end-frames 15, are rocked upon the shaft 14 so that the gear-wheels 19 are brought into mesh with the several racks 5 which have been moved from their normal positions; the rock snart 9 contacts with and drives forward the previously operated sectors 6, which being constantly in mesh with said racks 5, operate to return said racks to their normal or primary positions by the time the lever 10 contacts with the stop 41 (see Figs. 2 and 3); and simultaneously the meshed gear-wheels 19, and their related disks 18, are turned one-tenth of a revolution to each unit of the numeral on the case indicated by the pointer on the knob 3 on the related rack 5. Simultaneously with the completion of this operation the roller 16 drops into the next cam on the cam-wheel 11, and allows the end-frames 15 to drop, thus removing the gear-wheels 19 from contact with the racks 5. When any gear-wheel 19 has been

forced to a complete rotation by the motion of its related rack 5, the stud 28 on the related disk 18 will have come into contact with the related secondary cam 23, and said 5 secondary cam 23 is brought into the position indicated in Fig. 8, the related detent 25 catching in the second notch in said secondary cam 23, and holding the projecting cam portion of said secondary cam 23 in the 10 path of its related primary cam 27 mounted on the shaft 14. (See Fig. 8.)

On the forward movement of the lever 10, the shaft 7 and the geared sector 30, mounted thereon, are turned one-fifth of a revolution, and the related pinion 32 is turned one 15 complete revolution, but the pawl 38, being thrown out of the notch in the sleeve 37, the eccentric 33 does not rotate, and, therefore, the shaft 14 and its primary cams 27 do not 20 rotate. When, however, the lever 10 is thrown back to its normal position, and the sector 30 is driven upward one-fifth of a revolution, and the pinion 32 is turned one full revolution, the pawl 38 catches in the notch in the 25 sleeve 37, and the eccentric 33 is forced to a complete revolution, and its related rack 34 meshing with the pinion 35 and the shaft 14 with its primary cams 27 to one full revolution forward, and 30 one full revolution backward. In the forward revolution of said primary cams 27 those of said cams 27 which are related to 35 such of the secondary cams 23 as are projected into their respective paths, force the said secondary cams 23 down out of their paths, bringing the noses of the related detents 25 out of the notch in the said secondary cams 23, and driving the studs 29 fixed on said operated secondary cams 23 against 40 their related actuating detents 22, and said actuating detents move the indicating disks 18, to which they are respectively related forward one-twentieth of a revolution (see Fig. 11.) As the shaft 14 carrying the primary 45 cams 27 completes its forward rotation, the cut out portions of said cams will be presented to the operated secondary cams 23, thereby permitting the springs 26 to return the operated detents 22 from the position 50 shown in Fig. 11 to the position shown in Fig. 8, during which movement the disks 18 previously operated one-twentieth of a revolution by the detents will be advanced an additional one-twentieth of a revolution 55 completing the transfer. This return movement of the detents will, through the pins 29 of the related secondary cams 23, cause said cams to be returned to the positions to which they are adjusted by the disks 19 passing from 9 to 0. On the backward movement of the primary cams 27 they contact with the secondary cams 23 (as shown in Fig. 12) and throw them back into their

primary positions shown in Figs. 2 and 7. Said secondary cams 23 thus remain out of 65 the paths of said primary cams 27 until they are respectively forced in their paths again by the operation just described.

In an operation of the machine where a transfer is caused by a transfer, such for instance, where several of the disks 18 stand at "9" and "1" is added to the disk of lower order, it is necessary that the secondary cams 23 be positioned to effect a transfer 70 during the one-twentieth of revolution imparted to the disks by the movement of their related detents 22 in an anti-clockwise direction, Fig. 8, because of the fact that the last half of the transfer movement is imparted after the shaft 14 carrying the primary 80 cams 27 has completed a full rotation in a clockwise direction, Fig. 8, at which time it would be too late to initially set the secondary cams 23 for the reason that said cams would be reset during the reverse rotation of the shaft 14 by the primary cams 27 carried thereby, consequently losing the transfer. It will thus be seen that by the construction described and shown and the proper proportioning of the various gears 85 on racks, sectors and pinions the indicating disks 18 are turned as desired, and as each peripherally numbered disk completes a revolution the adjacent disk indicating the next higher denomination of units is rotated to 90 the extent of one figure, and the adding proceeds regularly and surely with the operation of the machine.

As hereinbefore stated I have shown and described only my invention and such parts 100 of a mechanism adapted to operate the same as I deem requisite to enable those conversant with the art to make and use the same, giving no description of the means necessary to record or visibly indicate the 105 various summations effected by the apparatus; such parts of a complete mechanism constituting a calculating machine, or indicating register of any kind, to which my construction may be applied, forming no 110 part of my invention or being necessarily shown or described with it to convey a full understanding of the construction and use of my invention.

Having thus described my invention, I 115 claim:

1. In a totalizer, the combination with a plurality of denominational elements, of devices for effecting transfers between said elements, and primary and secondary cams 120 for operating said devices, one of said cams being so positioned by its related denominational element as to be actuated by its companion cam for the purpose of effecting a transfer.

2. In a machine of the character described,

- the combination of indicating devices; means for differentially operating the same, and other means, one for each indicating device, including a single member to operate and limit the motion of each device.
3. In calculating or like mechanisms, the combination of a plurality of indicating wheels; actuating detents to turn said wheels and limit their rotation, and means, independent of said actuating detents, adapted to turn said indicating wheels.
4. In calculating or like mechanisms, the combination of a plurality of indicating wheels; actuating detents to turn said wheels and limit their rotation; means, independent of said actuating detents, adapted to turn said indicating wheels, and means for actuating said detents independently of said wheels.
5. In calculating or like mechanisms, the combination of a plurality of indicating wheels; actuating detents to turn said wheels and limit their rotation; means, independent of said actuating detents, adapted to turn said indicating wheels; means for actuating said detents independently of said wheels, and means, carried by a wheel of lower denomination, adapted to project the actuating means for the detent related to the wheel of a higher denomination into the path of travel of its related primary actuator.
6. In calculating or like mechanisms, the combination of a plurality of indicating wheels; actuating detents to turn said wheels and limit their rotation; means, independent of said actuating detents, adapted to turn said indicating wheels; means for actuating said detents independently of said wheels; means, carried by a wheel of lower denomination, adapted to project said actuator for the detent related to the wheel of a higher denomination into the path of travel of its related primary actuator; and a primary actuator for advancing the related displaced actuator for said detent, and, through it, its related wheel.
7. In a machine of the character described, transfer mechanism comprising oscillating spring-tensioned actuating detents, and mechanically operative means for successively actuating said detents.
8. In a machine of the character described, the combination of indicating devices; means for differentially operating the same, and oscillating detents, one for each indicating device, adapted to actuate and to limit the motion of said indicating device.
9. In a machine of the character described, the combination of a plurality of indicating wheels; oscillating spring-tensioned detents, normally positioning said wheels, but when oscillated rotating and controlling said wheels, and means independent of said detents, adapted to turn said indicating wheels.
10. In a machine of the character described, the combination of a plurality of indicating wheels; oscillating spring-tensioned detents, normally positioning said wheels, but when oscillated, rotating and controlling said wheels; means independent of said detents adapted to turn said indicating wheels, and means for actuating said detents independently of said wheels.
11. In a machine of the character described, the combination of a plurality of indicating wheels; oscillating spring-tensioned detents, normally positioning said wheels, but when oscillated, rotating and controlling said wheels; means independent of said detents adapted to turn said indicating wheels; means for actuating said detents independently of said wheels, and means carried by a wheel of lower denomination, adapted to project the actuating means for the detent related to the wheel of a higher denomination into the path of travel of its related primary actuator.
12. In a machine of the character described, the combination of a plurality of indicating wheels; oscillating spring-tensioned detents, normally positioning said wheels, but when oscillated, rotating and controlling said wheels; means independent of said detents adapted to turn said indicating wheels; means for actuating said detents independently of said wheels, and means carried by a wheel of lower denomination, adapted to project the actuating means for the detent related to the wheel of a higher denomination into the path of travel of its related primary actuator, and a primary actuator for advancing the related displaced actuator for said detents, and, through it, its related wheel.
13. In calculating or like mechanisms, the combination of a plurality of indicating wheels; actuating detents to turn said wheels and limit their rotation; means, independent of said actuating detents, adapted to turn said indicating wheels; means for actuating said detents independently of said wheels; means, carried by a wheel of lower denomination, to project said actuator for the detent related to the wheel of higher denomination into the path of travel of its related primary actuator; a primary actuator for advancing the related displaced actuator for said detent, and, through it, its related wheel; and a pawl for holding said detent actuator in different positions to which it is forced by said means carried by said wheel and by its related primary actuator.
14. In calculating or like mechanisms, the combination of a plurality of indicating wheels; actuating detents positioned to turn said wheels; means, independent of said actuating detents, adapted to turn said indicating wheels; means for actuating said de-

tents independently of said wheels; means, carried by a wheel of lower denomination, to project said actuator for the detent related to the wheel of a higher denomination 5 into the path of travel of its related primary actuator; a primary actuator for advancing the related displaced actuator for said detent, and, through it, its related wheel, a pawl for holding said detent actuator, in 10 different position to which it is forced by said means carried by said wheel, and its related primary actuator; and means for rotating, in one direction, said primary actuator to advance said displaced actuator, and 15 reversely rotating it to return said actuator to its initial position.

15. In calculating or like mechanisms, the combination of an adding mechanism, containing a series of indicating wheels; gear 20 wheels connected with said indicating wheels; manually movable racks normally out of engagement with said gear wheels; means for rocking said adding mechanism, whereby said gear wheels may be thrown 25 into and out of engagement with said racks; means for driving said racks to rotate said gear wheels when engaged therewith; detents for actuating said gear wheels independently of said racks; secondary cams between said wheels, means on said indicating wheels for driving said secondary cams; means on said secondary cams for driving the detents actuating the gear wheels of higher denomination; primary cams for 30 operating said secondary cams, and means for rotating and reversely rotating said primary cams.

16. The combination of a pivoted frame; an adding mechanism contained within said 40 frame; an actuator to operate said adding mechanism; a series of cams lying in a single plane and rotatable in one direction, about a common axis, and so positioned, as, when operated, to rock said pivoted frame, 45 and force said adding mechanism into engagement with said actuator to be actuated thereby, and to disengage said elements after actuation; means for operating said actuator while engaged with said adding 50 mechanism, and a lever adapted to operate said cams by its partial rotation.

17. The combination of an adding mechanism; a series of actuators therefor; a rotatable disk carrying a plurality of cams 55 contacting with said adding mechanism; means for partially rotating said disk at each operation thereof, whereby said adding mechanism and selected actuators are thrown into engagement, and are held in engagement during operation of the adding mechanism, and disengaged when such operation is completed; means for rotating said disk, and means for driving said actuators.

18. In a totalizer, the combination with a

plurality of denominational elements, of 65 means for differentially actuating said elements, retaining devices for holding said elements in their actuated positions, and means for operating said retaining devices for the purpose of effecting a transfer. 70

19. In a totalizer, the combination with a plurality of denominational elements, of means for differentially actuating said elements, retaining devices for holding said elements in their actuated positions, members 75 controlled by the totalizer elements for operating the retaining devices for the purpose of effecting a transfer, and means for actuating the positioned members.

20. In a machine of the class described, 80 the combination of a totalizer element, a detent therefor operable to actuate said element, a secondary actuator for operating the actuating detent to actuate the element, a primary actuator operated at each operation 85 of the machine, and means carried by the totalizing element for establishing a coöperative relation between the primary and secondary actuators.

21. In a machine of the class described, 90 the combination of a totalizing element, a detent therefor operable to actuate said element, a secondary actuator for operating the actuating detent to actuate the element, means carried by the totalizing element for 95 giving the secondary actuator a preliminary movement upon certain adjustments of said element, and a primary actuator for operating the secondary actuator when so moved.

22. In a machine of the class described, 100 the combination of a totalizing element, a detent therefor operable to actuate said element, a primary actuator operated at each operation of the machine, a secondary actuator and means carried by the totalizing element for 105 moving said secondary actuator to establish a coöperative relation between the primary actuator and the actuating detent.

23. In a machine of the class described, 110 the combination of a totalizing element, transfer mechanism therefor including a reciprocatory pallet one arm of which normally holds the element in a position of adjustment the other arm being adapted to engage and actuate the element upon a reciprocation of the pallet, and means for reciprocating the pallet.

24. In a machine of the class described, 120 the combination of a totalizing element, transfer mechanism therefor including a reciprocatory pallet for holding the element in a position of adjustment and to actuate the element to effect a transfer, a primary actuator for operating the pallet, a secondary actuator and means carried by the totalizing element for adjusting the secondary actuator to establish a coöperative relation 125 between the primary actuator and pallet.

25. In a machine of the class described, the combination of a totalizing element, transfer mechanism therefor including a reciprocatory pallet for holding the element in a position of adjustment and to actuate the element to effect a transfer, a secondary actuator for operating the pallet to actuate the element, means carried by the totalizing element for giving the secondary actuator a preliminary movement upon certain adjustments of said element, and a primary actuator for operating the secondary actuator when so moved.
26. In a machine of the class described, the combination of a totalizing element, a detent therefor operable to actuate said element, a secondary actuator for operating the actuating detent to actuate the element, means carried by the totalizer element for giving the secondary actuator a preliminary movement upon certain adjustments of said element, detent means for temporarily holding the secondary actuator, and means for operating the secondary actuator when so moved.
27. In a machine of the class described, the combination of a totalizing element, a detent therefor operable to actuate said element, a secondary actuator for operating the actuating detent to actuate the element, means carried by the totalizer element for giving the secondary actuator a preliminary movement upon certain adjustments of said element, and a primary actuator for first operating the secondary actuator when so moved and finally restoring said secondary actuator to normal position.
28. In a machine of the class described, the combination of a totalizing element, transfer mechanism therefor including a reciprocatory pallet for holding the element in a position of adjustment and to actuate the element to effect a transfer, spring means for holding said pallet in holding position and means for positively reciprocating said pallet to actuate the element.
29. The combination with a totalizer comprising a plurality of denominational elements, of devices for effecting transfers between said elements, the said devices being positioned under the control of the totalizer elements, and reciprocatory actuators for the transfer devices, the said actuators being constructed while moving in one direction to actuate the positioned devices to effect transfers and while moving in the opposite direction to reset the positioned devices.
30. The combination with a totalizer comprising a plurality of denominational elements, of devices each composed of two parts for effecting transfers between said elements, one part of each device being positioned under the control of its related totalizer element; and reciprocatory actuators for the transfer devices, the said actuators being constructed while moving in one direction to actuate the positioned devices to effect transfers and while moving in the opposite direction to reset the positioned devices.
31. The combination with a totalizer comprising a plurality of denominational elements, of devices for effecting transfers between said elements, driving members for said devices, the said members being brought into coöperative relation with the transfer devices under the control of the totalizer elements; and reciprocatory actuators for the driving members, the said actuators being constructed while moving in one direction to actuate the driving members in coöperative relation with the transfer devices to effect transfers and while moving in the opposite direction to reset the driving members to normal position.
32. The combination with a totalizer comprising a plurality of denominational elements, of oscillatory devices for effecting transfers between said elements, driving members for said devices, the said members being brought into coöperative relation with the transfer devices under the control of the totalizer elements, actuators for operating the driving members that are in coöperative relation with the transfer devices thereby partially effecting transfers, and springs for restoring said devices for the purpose of completing the transfers.
33. The combination with a totalizer comprising a plurality of denominational elements, of oscillatory devices for effecting transfers between said elements, driving members for said devices, the said members being brought into coöperative relation with the transfer devices under the control of the totalizer elements, reciprocatory actuators for operating the driving members that are in coöperative relation with the transfer devices thereby partially effecting transfers, and springs for restoring said devices for the purpose of completing the transfers, the operated driving members being restored to their normal position by the return movement of the actuators.
34. In a machine of the class described, the combination with a totalizer comprising a plurality of elements, of a series of adjustable slides for actuating the elements of the totalizer, the said slides and totalizer being normally out of operative relation, a rotatable disk carrying a plurality of cams and having connections for establishing operative relation between the totalizer and actuating slides, means for rotating the disk, and mechanism controlled by the latter means for restoring the actuating slides to

normal position when they engage with the totalizer elements for the purpose of actuating the latter.

35. In a machine of the class described, 5 the combination with a totalizer comprising a plurality of elements, of a series of adjustable slides for actuating the elements of the totalizer, the said slides and totalizer elements being normally out of coöperative 10 relation, a rotatable disk carrying a plurality of cams and having connections for

rocking the totalizer elements into engagement with the actuating slides, means for rotating the disk, and mechanism controlled 15 by the latter means for restoring the actuating slides to normal position when the totalizer elements are engaged therewith for the purpose of actuating the latter.
